FACSIMILE TRANSMITTER

Application filed October 6, 1930. Serial No. 486,662.

Our invention relates to the transmission of pictures, images, printed matter or the like wherein a beam of light is caused to traverse successive elements of a subject, the 5 resultant light variations being subsequently translated into corresponding electric currents for transmission over wires or through the ether.

More particularly, our invention relates to 10 improvements in chopper mechanism normally used in facsimile transmission systems.

A general layout of facsimile-transmission systems, according to the prior art, comprises a source of light for the purpose of producing 15 a light beam with which to scan a picture or view to be transmitted. The dimensions of the beam are controlled by a mask surrounding or enclosing said light source, a slit or other small opening in said mask determining 20 the physical dimensions of said beam. A chopper mechanism, comprising means for interrupting said light beam at an audio-frequency rate of approximately 2000 interruptions per second, is inserted in the path of the 25 beam.

This chopper mechanism, as disclosed by the prior art, usually takes the form of a disc having a plurality of light passages dispersed about its circumference. The interrupted 30 light beam is condensed or focused upon the picture or subject to be transmitted, the picture or subject being so moved with respect to the beam as to cause the interrupted light beam to scan all the elements of the picture.

The light, as affected by the picture elements, is subsequently translated into corresponding 35 electric currents and transmitted in this form. At the receiving end, the process is substantially reversed to reproduce the transmitted 40 picture.

Were no chopper mechanism to be used, the current in the photo-cell circuits would, accordingly, be modulated only by the variations 45 in the intensity of the various picture elements, the frequency of the currents being either below the range of audio-frequency or of a frequency close to the lower limit of audio-frequencies. Currents of such low frequencies cannot be efficiently amplified by 50 any known amplifying means. The purpose

of the chopper mechanism, therefore, is to superimpose upon the currents a frequency well up in the audio range, whereby efficient amplification for the purpose of transmission may be obtained.

In present day systems, there are two main factors which determine the efficiency and quality with which pictures may be transmitted, and these are, first, the intensity of the light beam used in scanning, and, second, the percentage of the light energy which can be caused to influence the photo-cells or photo-sensitive devices employed in the system. In the arrangement described above wherein the source of light is substantially totally enclosed, the intensity of the source is limited because of the heat generated by it in the limited space bounded by the mask.

According to our invention, we are enabled to utilize a very intense source of light. We 70 accomplish the above result, broadly, by controlling the temperature of the medium about the source of energy.

It is, accordingly, one object of our invention to provide means, in facsimile transmitters, whereby it becomes possible to generate 75 a beam of energy of great intensity for scanning purposes.

Another object of our invention is to provide a chopper mechanism for a facsimile 80 transmitter which is adapted to function as a cooling agent for a light-ray-generating source.

Another object of our invention is to provide means for causing circulation of air 85 about heated portions of a facsimile transmitter.

Additional objects of our invention will be pointed out in detail in the following description, taken in conjunction with the accompanying drawing wherein:

Figure 1 is a plan view of a facsimile transmitter embodying our improvements.

Fig. 2 is a view, in cross section, of the chopper mechanism along the plane II-II 95 of Fig. 1.

Referring more particularly to the drawing, the transmitter comprises, in general, a source of light energy, a chopper mechanism, indicated broadly by reference numeral 3, a 100

picture-supporting means 5 and photo-sensitive devices 7 associated therewith. The light generated by the source is emitted through a slit 9 in the masking element 11, and is focused upon a view 13 to be transmitted. The view is supported or wrapped about the rotatable support or cylinder 5 which, in addition to its movement of rotation, is also caused to assume a translatory motion. With a stationary beam of light focused upon the picture 13, the movement of the picture relative thereto will thereby cause the beam to scan the entire picture. The light reflected from the picture will be modified or modulated by the various picture elements scanned. This reflected light is caused to fall upon or strike the cathodes of the pair of photosensitive devices 7 located in close proximity to the picture and adjacent to the light ray. The effect of the reflected light upon the photo-sensitive devices will be to modulate current in the photo-sensitive-device circuits in a manner which will closely simulate the modulations of the light ray.

Referring more particularly to our improved chopper mechanism, it takes the form of an element 15 of can-shape open at one end and mounted on a shaft 17 at the other end, whereby the chopper may be rotated at any desired speed. The chopper element is slipped over and encloses the light source 1 and its protecting mask 11, sufficient space being provided between said elements to allow for circulation of air. Dispersed about the cylindrical surface of the chopper, we provide a plurality of slots 19, the distance between said slots being sufficient to cover the slit or opening 9 in the mask, whereby the ray of light passing through said slit may be effectively interrupted at a frequency which will be determined by the number of such slots in the chopper mechanism, and the speed of rotation of the same.

Because of the particular construction of our chopper apparatus, a fan action will be obtained during its operation and, since the mask is substantially unobstructed or opened at both ends, except for a light-source supporting element (not shown) within one end, a path is provided for the circulation of air about the source of light. The rotation of the rotating chopper member will cause the heated air to be drawn through one end of the mask, this air being replaced by an inrush of cooler air through the other end of the mask, thereby providing a constant cooling effect upon the source of light energy. Because of this improved result, as obtained by our chopper device, we are enabled to make use of a source of light of great intensity, with the ultimate result that the intensity of the light beam striking the picture will be of much greater value, resulting in a

received picture of excellent quality and reproduction.

Various other forms of our device may readily suggest themselves without departing from the scope of our invention. The fan action of our device, for example, may be greatly enhanced by providing fins or vanes on our chopper, whereby a more powerful effect may be produced on the enclosed air. Therefore, while we have disclosed our invention in great detail, we do not desire to be limited to such except insofar as is necessitated by the prior art and the spirit of the appended claim.

We claim as our invention:

In a view-transmission system, a source of energy, an open ended masking element for said source provided with a slit for producing a ray, and means associated therewith for interrupting said ray, said means comprising an element substantially enclosing said source of energy and said mask and provided with a plurality of openings whereby said ray of light may be interrupted by movement of said element relative to said source of energy.

In testimony whereof, we have hereunto subscribed our names this 30th day of September, 1930.

HOWARD M. ELSEY.
